United States Patent Office

Des. 211,292
Patented June 4, 1968

211,292

ADDING MACHINE OR SIMILAR ARTICLE

Pierre L. Crease, Kettering, and Albert J. Michaud, Jr.,
Englewood, Ohio, assignors to The National Cash
Register Company, Dayton, Ohio, a corporation of
Maryland

Filed Nov. 20, 1967, Ser. No. 9,473

Term of patent 14 years

(Cl. D64—11)

FIG.1

FIG.2

FIG. 3

FIG. 4

FIG. 1 is a front perspective view of an adding machine or similar article showing our new design;

FIG. 2 is a rear perspective view thereof;

FIG. 3 is a right side elevational view; and

FIG. 4 is a top plan view thereof.

The dominant features of our design reside in the full-line portions of the drawings.

We claim:

The ornamental design for an adding machine or similar article, as shown and described.
